UNITED STATES PATENT OFFICE.

GEORGE B. SOUTHDARD, OF REDLANDS, CALIFORNIA, ASSIGNOR OF ONE-FOURTH TO NETTIE N. CHILDS AND ONE-FOURTH TO THERESA A. NYE, BOTH OF LOS ANGELES, CALIFORNIA.

MECHANISM FOR FORMING PLANTING-POTS.

1,147,276.

Specification of Letters Patent. Patented July 20, 1915.

Application filed February 16, 1914. Serial No. 818,858.

To all whom it may concern:

Be it known that I, GEORGE B. SOUTHDARD, a citizen of the United States, residing at Redlands, in the county of San Bernardino, State of California, have invented new and useful Improvements in Mechanisms for Forming Planting-Pots, of which the following is a specification.

This invention relates to a mechanism for forming planting pots of sheet material, and particularly pertains to a device for forming the pots constituting the subject matter of an application for Letters Patent on planting pots filed coincidently herewith.

15 In the manufacture of the planting pot above referred to it is necessary to form a rectangular blank into a cylinder by overlapping its ends and inserting the terminations of a wire through perforations in the overlapped ends of the blank, and to provide means for facilitating the folding of the end of the cylinder thus formed to provide an apertured bottom for the pot and supporting members therefor.

20 25 It is the object of this invention to provide a device for facilitating the above operations and by which pots of a uniform size and construction can be readily obtained and which is adapted to be adjusted to vary 30 the size of the pot.

A further object is to provide a machine of the character referred to which is cheap in construction and simple and efficient in operation, and which machine is particularly 35 adapted for use by nurserymen and the like to enable the forming of planting pots as they are needed.

The invention primarily resides in a forming member or mandrel of cylindrical shape 40 having channels on its periphery and formed with a groove on its upper end having inclined side walls terminating at their upper edges with downwardly inclined faces intersecting the periphery of the forming 45 member or mandrel and means coöoperating with said channels to perforate the overlapped edges of a blank bent around the forming member or mandrel.

The invention is illustrated in the accompanying drawing, in which:

Figure 1 is a view in side elevation of the

preferred form of the invention in which the forming member is stationary and the blank perforating means movably mounted. Fig. 2 is a side elevation of a modified form 55 of the invention in which the forming member is movably mounted and the perforating member stationary. Fig. 3 is an enlarged horizontal section on the line 3—3 of Fig. 1, showing the perforating device in its innermost perforating position. Fig. 4 is a detail horizontal section on the line 4—4 of Fig. 1. Fig. 5 is a perspective view of the blank forming member. Fig. 6 is a side elevation of same showing the blank in position thereon and illustrating the manner of inserting the fastening wire in place. Fig. 7 is a perspective view of the completed pot as seen from its bottom end.

More specifically, in the preferred form 70 of the invention, shown in Fig. 1, 8 indicates a cylindrical forming member or mandrel rigidly mounted on a base 9 and preferably inclined at a slight angle to the vertical. Formed in the inclined face of the forming 75 member 8 is a concave depression 10, the purpose of which will appear hereinafter, and formed in the forming member above and below the depression are alined grooves or channels 11 and 12 adapted to receive 80 perforating blades 14 and 15 carried on a rocking frame 16. The frame 16 is mounted on a shaft 17 supported in bearings 18 on the base 9, which shaft is adapted to be rocked manually to move the perforating 85 blades 14 and 15 in and out of engagement with the channels 11 and 12, and for this purpose is fitted with a crank arm 19 secured to the outer end of the shaft and connected to a foot lever 20 by means of a connecting 90 rod 21. The foot lever 20 is pivoted at 22 to a suitable support as a bench leg 23. Means are provided for normally maintaining the blades 14 and 15 in their retracted position, which means is here shown as consisting of a spring 24 connected to the crank arm 19 and to the block 9 in such manner as to normally exert an upward pull on the crank arm 19 to dispose the frame 16 in its 95 rearmost position.

The upper end of the forming member 8 is provided with a diametrical groove 25

having inclined side walls terminating at their upper edges as at 26 in downwardly inclined faces 27 intersecting the periphery of the forming member. The groove 25 is thus V-shaped in cross section and extends at right angles to the face of the blank on which the channels 11 and 12 are formed. The ends of the side walls of the groove 25 are beveled at their intersection with the periphery of the molding member as indicated at 28 to facilitate the bending of paper or similar sheet material thereover.

Mounted on the forming member 8 is a split ring 29, the ends of which are secured together by a screw 30 by which the split ring 29 can be clamped in any desired position on the forming member. The split ring 29 has a flange 31 on its upper edge, which flange forms a seat for the blank and serves 20 as a guide or gage for positioning the blank on the forming member or mandrel.

In the operation of the preferred form of the invention, just described, a rectangular blank 32 of paper or similar material is passed around the forming member 8 with its ends overlapping the channels 11 and 12, as particularly shown in Fig. 3; the lower edge of the blank resting on the flange 31 and the upper edge projecting a short distance above the upper end of the forming member 8, as indicated in dotted lines in Fig. 2, and manually retained in this position. The frame 16 is then rocked forward through the medium of the foot lever 20 or 35 in any other suitable manner to cause the perforating blades 14 and 15 to advance and pass through the overlapped edges of the blank 32 and enter the channels 11 and 12 and thereby form a pair of spaced perforations 33 in the blank. The frame 16 is then retracted by the action of the spring 24 and the ends of a wire 34 are introduced through the perforations 33, as shown in Fig. 6; the blank 32 being pressed into the depression 40 10 by the thumbs of the operator to facilitate the disposing of the wire 34 in its engaged position. The depression 10 also serves as a means to position the thumbs of the operator clear of the frame 16 and the perforating 45 points 14 and 15, while holding the blank sheet in position on the forming member. After the wire is in place the portion of the cylinder formed by the blank projecting above the member is bent inwardly at the 50 ends of the V-shaped channel 25 to form the bottom members —a— and —b— of the pot, as shown in Fig. 7. The portion of the blank extending above the forming member is of such length that when turned as just 55 described the adjacent edges will be spaced a short distance apart to form an aperture —c—. To complete the pot the upwardly projecting portions of the blank at the front and rear of the forming member are then

folded downwardly over the inclined walls 65 of the V-shaped groove 25 as shown in Fig. 6, thus forming the supporting members —e— and —f— of the pot, as shown in Fig. 7. The pot thus formed may now be readily removed from the forming member and the 70 operation repeated.

In the modified form of the invention shown in Fig. 2, the frame 16 is rigidly mounted on the base 9 and the forming member 8 is pivoted at 35 to swing in relation to the frame 16. In the operation of this form of the invention the forming member 8 is rocked manually to move the blank thereon in and out of engagement with the perforating blades 14 and 15.

By adjusting the split ring 29 pots of various depths may be formed on the single forming member. By providing a series of forming members of different diameters pots of various sizes can be made.

In order to adjust the perforating members in relation to the frame 16 they are preferably formed with threaded shanks 36 which are engaged by nuts 37 screwed on opposite sides of the frame 16 through which 90 the shanks 36 pass; washers 38 being interposed between the nuts 37 and the frame 16. The perforating members 14 and 15 are preferably formed with knife edges so as to form elongated perforations in the blank.

What I claim is:

1. A device for forming planting pots of the character described, comprising a cylindrical forming member having a depression on its cylindrical periphery and a depression 100 on its upper end and formed with aligned channels above and below the first named depression thereon, and means coöperating with said channels to form a perforation in a blank surrounding the forming member.

2. A device for forming planting pots, comprising a cylindrical forming member having a depression on its cylindrical wall, aligned channels on opposite sides of the depression, perforating means adapted to co-operate with said channels to perforate a blank surrounding said forming member, and a blank positioning collar adjustably mounted on the forming member.

3. In a machine of the class described, a 115 container forming mandrel having a vertically disposed channel and a depression on its peripheral surface, said depression being located on the surface of said mandrel intermediate the ends of the channel, and a blank 120 perforating mechanism mounted adjacent said mandrel adapted to co-act therewith in the formation of a container.

4. In a machine of the class described, a substantially cylindrical forming member 125 having a depression formed on its upper end and on its periphery, it being also provided with vertically disposed grooves in its

peripheral surface, said grooves opening into the depression formed therein, said forming member adapted to receive the blank of flexible material used in a container, and perforating means mounted adjacent said forming member and co-acting therewith in the formation of the container.

In witness that I claim the foregoing I have hereunto subscribed my name this 30th day of January, 1914.

GEO. B. SOUTHARD.
